UNITED STATES PATENT OFFICE.

ANDREW BODOR, OF IRVINGTON, NEW JERSEY, ASSIGNOR, BY MESNE ASSIGNMENTS, TO REINFORCED PAPER BOTTLE CORPORATION, OF NEW YORK, N. Y., A CORPORATION OF DELAWARE.

APPARATUS FOR MAKING PAPER BOTTLES.

Application filed June 9, 1924. Serial No. 718,758.

Among the principal objects which the present invention has in view are: To bottom a liquid container, constructed from fibrous material; to form a liquid-tight joint between 5 said container and the bottom thereof to accurately dispose said bottom in the body of said container; to expedite the operation of bottoming the container; and to simplify the construction of the apparatus for attaining 10 said purposes.

Drawings.

Figure 1 is a front elevation of an apparatus functioning to accomplish the purposes 15 above set forth, said apparatus being constructed and arranged in accordance with the present invention.

Figure 2 is a side elevation of the same partly in section, the section being taken on 20 the line 2—2 in Figure 1.

Figure 3 is a top plan view of the construction shown in Figure 1, partly in section, the section being taken as on the line 3—3 in Figure 1, the spinning head and gear train there- 25 for being shown as in extended position.

Figure 4 is a vertical section of a fragment 30 of the receiving end of the apparatus herein disclosed and the mechanism for delivering the blank from which the bottom is constructed to said receiving end, the same being shown as in action, the section being taken as on the line 4—4 in Figure 1.

Figure 5 is a similar view showing the gum spreading mechanism as in active position.

Figures 6, 7 and 8 are perspective views 35 showing, progressively, the installation of the bottom of the container within the end of a body thereof.

Figure 9 is a similar view on reduced scale 40 showing the steps by which the disk-like blank from which the bottom is formed, is installed and coiled to form a liquid-tight seam and reinforced support.

Figure 10 is a front elevation of the body 45 clamp with which the apparatus is provided for holding the bottom-receiving end of the body while the bottom is being installed therein.

Figure 11 is a longitudinal section of the 50 apparatus showing the body clamp in active relation to the body of a bottle and the bottom thereof, and the spinning mechanism for curling the end of the body and the flange

portion of the bottom to form the reinforced bottom edge above referred to.

Figure 12 is a similar view showing the spinning or curling apparatus removed from the container and the clamp partially collapsed and removed from the container bottom.

Figure 13 is a similar view showing the members of which the body clamp is constructed totally collapsed in position to pass through the neck or pouring end of the container.

Figure 14 is a schematic view showing the relation of the inner and outer members of the collapsible body clamp.

Figure 15 is a series of diagrams for illustrating the relative movements of the inner 70 and outer members of the body clamp and mechanism for operating the same, the progressive figures showing the clamping members in their fully inactive position progressively to the fully active position and the first 75 step in the retraction therefrom.

Description.

The apparatus herein disclosed is designed to perform one of a series of separate operations looking to the manufacture of liquid containers from paper having a laminated body provided with a shaped neck or pouring end and a liquid-tight bottom and reinforced supporting edge therefor. The apparatus is particularly designed for installing and finishing the bottoms referred to. The bottoms referred to are installed in tubular bodies which have been shaped and finished in an apparatus disclosed in the application for patent upon improvements in apparatus for making paper bottles, filed by me the 31st day of May, 1924, said application having assigned thereto the Serial Number 716,968, to which application, cross reference 85 is here made.

These bodies C are disposed in a cylindrical holder 20, the supporting frame 21 whereof is shaped to fit the cylindrical portion of the said body, as is best shown in Figures 11, 100 12 and 13 of the drawings. The opposite end of the holder 20 is pierced to support a horizontally disposed tubular plunger 22. The forward end of the plunger 22 is slotted longitudinally to provide guides for the relatively thin arms 23 and 24 of the body clamp 105

members which are designed to hold the body C immovable in the holder 20, while the bottom forming blank 25 is being installed and shaped. This construction is shown best in 5 Figure 10 of the drawings.

The body clamp members above referred to are constructed and arranged to form two sets. The set having the arms 24 have heads 26, the outer sides of which are curved in correspondence with the container body C. The longitudinal side edges of the heads 26 are disposed in planes parallel with the arms 23. 10

The heads 26 and 27 when combined and arranged interleave snugly and form a continuous ring, the sections whereof independently press upon the container body C to clamp it against the wall of the holder 20 adjacent the exterior opening of the frame 21, as seen best in Figure 10 of the drawings. 15

20 It will be noted by reference to Figures 10 and 14, that the longitudinal side edges of the heads 27 form recesses into which the heads 26 enter and completely fill. The side edges of the heads 27 are shaped or splayed 25 to form a slight "draft" for the heads 26 as the same are withdrawn.

In Figures 10 to 13 inclusive, there is best shown the mechanism for operating the arms 23 and 24. This consists primarily in 30 the tube 28, rod 29 and the rocking lever 30 engaging same. The lever 30 is coupled with a manually rocked lever 31 by means of a link 32 at the rear end of which is a recess 33 for engaging a pin 34 at the lower end 35 of the lever 30.

40 Adjustably mounted in the end walls of the recess 33 are screws 35, the arrangement of which is used for timing the engagement between the levers 30 and 31. This construction provides for certain necessary lost motion transmitted from the lever 31, which as shown best in Figure 2 of the drawings, is operated by a hand lever 36. The lever 31 has a reduced end 37 which normally engages 45 a recess 38 in the plunger 22. It is obvious that as the lever 31 is rocked on the shaft 39, the plunger 22 is reciprocated lengthwise of the holder 20. The limit of the forward movement of the plunger 22 is shown in 50 Figure 11, where the forward end of the plunger 22 rests firmly against the blank 25, which forms the bottom of the container C. In Figure 13, the extreme rearward movements of the plunger 22 and parts 55 associated therewith, are shown, the forward end thereof being withdrawn from contact with the bottom 25.

As best seen in Figure 3 of the drawings, the lever 30 is bifurcated, the extremities of 60 the bifurcated parts bearing upon the washer 41 and disk 44. The lever 30 is rocked on its shaft 42 from the position shown in Figure 13 of the drawings to the position shown in Figure 11, in correspondence with and when 65 actuated by the lever 31. The lever 31 is

manually manipulated by the hand lever 36. The lever 36 is manipulated after the body C of the bottom has been adjusted within the apparatus. To maintain the body in position and to regulate the insertion of the bottom of the bottle and resist the thrust of the edge turning mechanism when operating thereon, the plunger 22 and parts connected therewith are moved forward and the arms 23 and 24 are spread firmly against the body portion to 70 clamp the same rigidly in position. 75

The foregoing is accomplished as follows:

Referring to Figure 13, it will be seen that the plunger 22 and parts connected therewith are in what may be termed the retracted position where the arms 23 and 24 are held within the circumference of the plunger 22, which thus permits the neck of the bottle passing over the said plunger. The body of the bottle having been thus installed, the lever 36 80 is operated to rock the lever 31 on its shaft 39. The reduced end 37 enters the recess 38 to engage the plunger 22. The continued rocking of the lever 31 advances the plunger 22 to the position shown in Figure 12 of the drawings, at which moment, the end 37 clears the recess 38 and the plunger 22 is held thereafter stationary. During this movement of the plunger 22 and the lever 31, the link 32 has moved over the pin 34 without affecting 90 the lever 30. The advancing screw 35 now engages the pin 34 and rocks the lever 30. It will now be noted that the further rocking of the lever 31 is ineffective to advance the plunger 22, as the curvature of the side 95 100 of the recess 38 coincides with the end 37 of the lever 31.

It will be noted in this connection that thereafter the lever 31 prevents the plunger 22 from being forced backward.

When the lever 30 is rocked forward as above described, it is from the position shown in Figure 13. The first part of this movement operates through the disk 44 to advance the rod 29 until the disk 44 impinges upon the nut 40 closing the space 43. The immediate result of this is that the arms 23 are rocked outwardly and slightly in advance of the movement of the arms 24. This is caused primarily by the ridges 46 at the forward end 110 of the rod 29 operating upon the teeth of the segments 45. 115

When the space 43 has been closed, and when the disk 44 engages the nut 40, the tube 28 is moved forward in company with the rod 120 29. Annular teeth on the tube 28 engage the teeth of the segment 49 of the arms 24 to rock the same arms in unison with the movement of the arms 23. The movement of the heads 26 and 27 at the ends of the arms 24 and 23 is so 125 timed, owing to the difference in length of the said arms, that the heads coincidently engage the body of the bottle C and press the same against the wall of the holder 20 rigidly. It will now be observed that in this position, the 130

plunger 22 is prevented by the lever 31 from retreating, while a similar purpose is served by the lever 30 for the rod 29 and the tube 28. In this way a solid wall is presented to receive 5 the blank 25 constituting the bottom of the bottle and to resist the pressure incident to overturning or spinning the flange 25^a and the edge of the body of the bottle.

When the edges have been spun as stated, 10 the body of the bottle is disengaged by the heads 26 and 27 of the arms 24 and 23 as the result of throwing the lever 36 backward. When this is done, the parts are moved from the position shown in Figure 11 where it will 15 be observed that the end 37 of the lever 31 enters the recess 38 to engage the same. As the plunger 22 is retracted, the lever 30, rod 29, and tube 28, are carried back to the position shown in Figure 12 of the drawings, in which 20 position the end 37 of the lever 31 is leaving the recess 38, thereby permitting the plunger 22 to rest. In this position the rearmost screw 35 has engaged the pin 34 so that the further rocking of the lever 31 rocks the lever 25 30 backward to the position shown in Figure 13. In this movement it will be observed that the pressure of the lever 30 being upon the disk 41, the rod 29 is primarily moved until the reduced end 46 thereof engages the end of 25 the tube 28. (See Figures 12 and 13.) The movement of the reduced end 46 rocks the arms 23 inward, subsequently the tube 28 is drawn back by the further movement of the lever 30 with the result that the reduced end 30 35 47 of the tube engaging the teeth of the segments 49 rocks the arms 24 to their folded position simultaneously, with the similar result upon the arm 23 caused by the further movement of the reduced end 46. Thus, after the 40 bottom has been placed and firmly secured in the bottle, the plunger 22 and the arms 23 and 24 connected therewith are folded to a diameter which freely passes through the neck of the bottle C, when the same is ejected by the 45 operation of the lever 93.

At the inner end of the shaft 64 is a worm wheel 66, the teeth whereof are engaged by a worm 67 on the driving shaft 68 of the apparatus. 50 It is obvious that this arrangement provides for continuously rotating the gear wheel 63, 62 and 57, but as can be seen in Figure 1 of the drawings, when the disk 53 is inactively disposed the wheel 56 is disengaged from the 55 wheel 57. When, however, the disk 53 is swung into position to enter the holder 20 and the end of the body C therein, the yoke 55 is swung as shown in Figure 5 of the drawings so that the wheel 57 is engaged by the wheel 60 56, the disk 53 thereafter rotating in unison with the shaft 63 and parts associated therewith. This provides for a relatively slow rotation of the disk 53, during the period when the disk is disposed within the end of the 65 body C.

This action is conducive to the spreading of adhesive with which the disk 53 is provided and which it collects from the raised edge 67^x of the well or reservoir 68^x, when manually moved thereto. 70

As soon as the adhesive is spread inside the extended edge of the body C, the disk 53 is withdrawn, the handle 69 being used for this purpose. The handle 70 thereafter serves to lower the gumming mechanism to its normal 75 or inactive position, as shown in Figure 1, where a new supply of mucilage is administered to the edge of the disk 53. It will be understood that in positioning the disk 53, the handle 70 is employed to swing the yoke 80 55 around the shaft 64, the wheels 62 and 63 permitting this movement. Preliminary to placing the disk 53 within the body of the container C, the yoke 59 is moved upon its pivots to engage the wheels 56 and 57 as 85 shown best in Fig. 5 of the drawings. Sufficient flexibility is allowed in the mechanism to permit the forward movement of the shaft 61 and the yokes 59 and 55 connected therewith to permit the movement of the disk 53 90 into, and the withdrawal from the body of the container C.

The necessary adhesive having been applied the next step in the operation is to place the disk 53 and to seat it properly within the 95 extended edge of the body C. In Figure 6 of the drawings, the disk is shown in its flat position disposed in front of or covering the open end of the body C. In Figure 4 of the drawings in broken lines, the disk is shown 100 as descending to enter the splayed or flanged edge 71 which guides the disk 53 into the receptacle slot 72 formed in the housing. 105

The means for reciprocating the plunger 51 in the housing 73 consists primarily of the 110 racked plunger 74, the teeth of which are engaged by a small pinion 75. The pinion 75 is mounted on a shaft 76 at the outer end whereof is provided a lever 77, best seen in Figure 1 of the drawings.

The lever 77 is used for rocking the shaft 76 and the pinion 75 thereon, with the result that the plunger 74 is retracted to a position outside of the slot 72, or advanced to a position inside of the slot 72. The diameter of 115 the interior of the housing 73 is such as to permit the edge of the disk 53 to fold over the cylindrical edge of the plunger 51. 110

In the operation of the plunger 51 and parts associated therewith, the disk 53 having been 120 deposited in the slot 72 while the plunger 51 is in its retracted position, the operator rocks the shaft 76 and wheel 75 by means of the lever 77, with the result that the racked plunger 74, the plunger 51, and the disk 53 are carried forward to the position shown in Figure 12: 4 of the drawings, the circular margin of the disk 53 being laid back over the plunger 51, as shown in the said Figure 4. Having deposited the disk 53 in the position shown in 130

Figure 4, the plunger 51 is retracted to the full of its movement to a position outside of the slot 72, when a succeeding disk 25 may be inserted in said slot.

5 As each bottom or disk 25 is placed in position, the housing 73 and parts associated therewith, are lifted to a position clearing the end of the holder 20. To this end the housing 73 is provided with bracket arms 78 which are
 10 pivotally mounted on a shaft 79.

The bracket arms 78 have shoulders 80 which rest upon stop pins 81 formed on the far side of the shaft 79 in the frame 21, as seen best in Figure 2 of the drawings. In this position, the housing 72 and parts associated therewith are thrown out of balance on the far side of the apparatus, leaving the space in front of the apparatus clear for the operation of the spinning or curling shaper 52.

The shaper 52 is mounted on a shaft 82 with the transmission gear wheel 83. The wheel 83 is driven from the shaft 84 by means of the train of gear wheels 85, 86 and 87, which are supported in a frame 88, having a hand-hold 89. The shaft 84 is driven from the shaft 68 through the gear wheel 90. The frame 88 is rotatively mounted on the shaft 84 while the gear wheel 85 is slidably keyed thereto. This arrangement provides for the movement lengthwise of the shaft 84 of the frame 88 and gear train associated therewith. Normally, the frame 88 and parts associated therewith are held outward from the frame 21 by the spring 91, as best seen in Figure 3 of the drawings. The limit of the outward movement of the frame 88 is controlled by the disk 92.

disk 32. When desiring to curl the end of the body C and the flange 25^a, the operator using the handle 89 swings the frame 88 around the shaft 84 to oppose the shaper 52 over the exposed end of the body C. At all times, the shaper 52 is rotating. When thereafter it is pressed upon 45 the said end of the body C and said flange, the said end and flange are overturned and curled to conform to the shape of the shaper 52 which is grooved, as seen best in Figure 11 of the drawings. The edge following the form of the 50 groove is overturned or curled. In practice the curled edge of the end of the body C and of the flange 25^a rests against the bottom forming portion of the disk 25, thereby constructing for the container C, a reinforced edge portion 55 for setting the container upon the reinforced portion referred to, being four-ply in thickness.

With the completion of the operation of the shaper 52, the operation of the present apparatus is completed, with the exception of the delivery of the container from the holder 20. This is accomplished by the stripping lever.

As best shown in Figures 11 to 13 inclusive, the lever 93 has a pivot shaft 94 and spreading vane arms 95. The extremities of the arms 95

bear upon the end of the container body C when the same is placed in the holder 20, as shown in the figures of the drawings referred to. When now, the shaper 52 as been removed from the path of the body C, the stripping lever 93 is manually rocked backward toward the rear of the apparatus with the result that the ends of the yoke arms 95 engage and press upon the pouring end of the body C, thereby forcing the body C outward from the holder 20 to a position where it is manually engaged and withdrawn from the said holder. 70 75

It will now be found that the container body is completely finished, having a liquid-tight bottom and a reinforced supporting edge 80 therefor, which is the result of the combined operations of an apparatus disclosed in application for patent bearing Serial Number 716,968 filed 31st day of May, 1924, and the apparatus disclosed in the present application for patent. 85

Claims:

1. An apparatus as characterized comprising a receptacle for holding an open-ended bottle body; expansible clamp members operatively mounted within said receptacle for expanding to compress said body against said receptacle while a bottom member is adjusted to and secured within said body, said clamp members being arranged in a plurality of groups; and means for moving said groups into operative relation to the bottle bodies successively. 90 95

2. An apparatus as characterized comprising a receptacle for holding an open-ended bottle body; expansible clamp members operatively mounted within said receptacle for expanding to compress said body against said receptacle while a bottom member is adjusted to and secured within said body, said clamp members being arranged in a plurality of groups; and means for moving said groups into operative relation to the bottle bodies successively, said means providing for the completion of the action of the groups simultaneously. 100 105 110

3. An apparatus as characterized comprising a receptacle for holding an open-ended bottle body; expansible clamp members operatively mounted within said receptacle for expanding to compress said body against said receptacle while a bottom member is adjusted to and secured within said body, said clamp members being arranged in groups, the members of each group being pivoted to rock into contact with said bottle body; and means for operating upon said groups successively to dispose the active ends of said groups in their final operating position.

4. An apparatus as characterized comprising a hollow cylindrical receptacle; an expandable clamp mounted therein concentric therewith, said clamp embodying a plurality of presser feet, each foot forming a segment of a clamping ring, the perimeter whereof ap- 130

proximates closely the circumferential dimension of the inner surface of the receptacle; and means operating for expanding said presser feet successively.

⁵ 5. An apparatus as characterized comprising a hollow cylindrical receptacle; an expandable clamp mounted therein concentric therewith, said clamp embodying a plurality of presser feet, each foot forming a segment of a

clamping ring, the perimeter whereof approximates closely the circumferential dimension of the inner surface of the receptacle; and means operating for expanding said presser feet successively, the swinging ends of said presser feet varying in length to arrive at full operating station, simultaneously.

ANDREW BODOR.
